POWDER PUFF AND METHOD OF MANUFACTURING THE SAME

Application filed July 23, 1928. Serial No. 294,736.

This invention relates to applicators, and refers particularly to an improvement in the construction of powder puffs and to a method of manufacturing the same.

Powder puffs as now generally made require a certain amount of hand work in the finishing operation, due to the fact that they are machine stitched except for a certain portion of their margin which is left open for the inversion of the puff body, after which the open marginal portion is closed by over stitching, necessitating the hand finishing operation. Obviously, hand work is expensive, in addition to the fact that it does not lend as neat an appearance to the finished article. It has also been observed that generally the hand work finishing operation is given out as home work, in which instances the puffs are not handled under as sanitary conditions as would be maintained in a factory or place of business.

The present invention, therefore, comprehends a powder puff structure and method of producing the same which is accomplished entirely by machine, thereby eliminating hand work and the objections and disadvantages incident thereto.

More specifically, the invention contemplates a powder puff constructed from a length of material which is folded upon itself and joined along its marginal side edges by an inwardly disposed seam which leaves the end edges unsecured to afford an opening through which the structure is inverted to allow for the disposal of the seam within the body of the puff and to permit of the introduction of the fingers to hold the puff for use.

Other objects and advantages reside in the novel features of construction, the simplicity of the method employed in producing the same and the general efficiency derived therefrom.

With the above recited and other objects in view, reference is had to the following description and accompanying drawings, in which there is exhibited one example or embodiment of the invention, while the claims define the actual scope of the same.

In the drawings:

Figure 1 illustrates the blank from which the body of the puff is constructed.

Figure 2 is a perspective view illustrating the initial step of the folding of the strip from which the body is constructed. 55

Figure 3 is a similar view illustrating the liner element applied and stitched to the body. 60

Figure 4 is a longitudinal sectional view taken approximately on the line 4-4 of Figure 1, illustrating the initial inversion of the liner and body with the filler in place. 65

Figure 5 is a similar view illustrating the final inversion of the body and the construction of the finished article. 65

Figure 6 is a perspective view of the finished puff.

Referring to the drawings by characters of reference, and particularly to the method of producing the puff, a length of material 10 cut to the desired size and shape is initially laid flat, as shown in Figure 1. It will be observed that the end edges are provided with a suitable binding 11 to prevent raveling, and preferably said edges are convex for a purpose to be hereinafter set forth. The strip or length of material 10 is preferably of plush or velvet or any other suitable material which has a nap 12 on one surface and a smooth finish on the opposite surface. The initial step consists in folding in the opposite ends so that the bound edges 11 are overlapped, as shown in Figure 2. A liner strip 13 is then superimposed over the strip when it is folded to the position illustrated in Figure 2, and the side edges 14 of the strip 10 and side edges 15 of the strip 13 are then joined by a line of stitching 16 completely passing therethrough, as illustrated in Figure 3. Preferably, this line of stitching is accomplished by machine and it will be observed that the strip 13 is of greater length than the folded strip 10 so that flaps 17 are provided which project beyond the folded ends of the strip 10, as clearly illustrated in Figure 3. The next step consists in inverting the structure thus formed so that the joined edges 14 and 15 of the strips 10 and 13 are disposed inwardly while the bound 70 75 80 85 90 95 100

edges 11 are exposed. In this position, the filler 18 of cotton wadding or the like is introduced and the projecting ends or flaps 17 of the liner strip 13 are tucked in between the body 10 and the filler 18 to cover and conceal the filler, as clearly illustrated in Figures 4 and 5. The final step consists in now inverting the strip 10 so that the ends having the bound edges 11 are brought together, as illustrated in Figures 5 and 6 with the nap surface 12 completely exposed. Due to the convexity of the bound edges 11 in the final form of the puff, said edges will be closely disposed adjacent each other to prevent gapping. The user may insert the fingers through the slot 19 which is provided between the bound edges 11 for the purpose of handling the puff to apply powder to the face. It is also obvious that the fingers may be inserted either way due to the fact that a double pocket 20 is formed between the liner strip 13 and the ends of the body 10 having the bound edges 11. From the foregoing operation, it will thus be seen that no hand stitching operation is required and hence the puffs will be of a more uniform nature, presenting a neater appearance and eliminating home work and the unsanitary conditions incident thereto. It is also apparent that when necessary the puff body may be inverted, the filler removed and the body washed, after which a new filler may be placed therein.

The completed powder puff is composed of a sheet or length of material 10 which has its opposite ends folded over the remaining portion and joined thereto by a stitched seam which is disposed within the confines of the puff body which is thus provided. In view of the fact that the bound end edges 11 are unsecured, it is obvious that a transverse slit or opening is afforded which allows for the inversion of the body and which affords means for the introduction of the fingers to hold the puff when in use. By providing a lining 13 between which and the remaining unslotted wall of the puff the material 18 is disposed, it is obvious that the user's fingers do not come in contact with the filling.

50 While the puff is illustrated as of square or rectangular configuration, it is to be understood that there is no intention of restricting the invention thereto and that other shapes may be resorted to which are possible.

55 What is claimed is:

1. A powder puff constructed from a length of material having its opposite ends folded over the remaining portion and joined thereto by an inwardly disposed stitched seam 60 with the edges of said ends unsecured to provide a transverse slit intermediate the length of the puff through which the fingers may be introduced for manipulating the puff, a filler within said body and a lining covering said filler and between which and the un-

slotted wall of the puff the said filler is positioned.

2. A powder puff constructed from a length of material having its opposite ends folded over the remaining portion and joined thereto by an inwardly disposed stitched seam with the edges of said ends unsecured to provide a transverse slit intermediate the length of the puff through which the fingers may be introduced for manipulating the puff, a filler within said body and a lining covering said filler and between which and the unslotted wall of the puff the said filler is positioned, the said lining being secured in place by the same line of stitching which joins the seam aforementioned.

3. A method of manufacturing powder puffs consisting in folding the ends of the length of body material over onto the remaining portion, superimposing a lining material thereon, stitching through the marginal side edges of the body and lining materials, inverting said joined body and lining materials, introducing a filling material therebetween and finally inverting the body material through the slit formed by the unsecured end edges thereof.

4. A method of manufacturing powder puffs including the steps of folding over the ends of a length of body material onto the remaining portion, so that the major portion of said ends lie in the same plane with each other and parallel to said remaining portion, stitching through the marginal side edges of said folded length of material and inverting said body through the slit formed between the unsecured end edges thereof.

5. A powder puff consisting of a single length of material having the opposite end portions thereof directed inwardly, lying in the same plane and disposed parallel to the remaining medial portion with the side edges of said portions folded laterally inward to a superimposed relation and means disposed within the confines of and concealed by the body for joining said inwardly folded superimposed side edges to provide said body with opposite walls, one of which is provided with a transverse slit as and for the purposes specified.

6. A powder puff including a hollow body constructed from a single piece of material having opposite end portions extending inwardly over the medial portion thereof lying in the same plane with each other, and disposed parallel to the medial portion thereof with the side edges of the end and medial portions projecting inwardly and internal concealed means joining said edges.

7. A rectangular piece of material having opposite end portions extending inwardly over, the medial portion thereof lying in the same plane with each other and disposed parallel to the medial portion thereof with the side edges of the end and medial portions

projecting inwardly and internal concealed means joining said edges.

8. A powder puff including a hollow body constructed from a single piece of material having opposite end portions extending inwardly over and disposed parallel to the medial portion thereof with the side edges of the end and medial portions projecting inwardly and means within the confines of and concealed by the body joining said edges.

9. A powder puff including a body formed of a single length of material having the opposite end portions thereof directed inwardly, lying in the same plane and parallel to the remaining medial portion with the side edges of said portions folded inward to a superimposed relation and internal concealed means joining said inwardly folded superimposed side edges to provide opposite walls, the end edges of said end portions being free and adjacent each other to provide a transverse slit intermediate the ends of one wall of the body.

10. A powder puff including a body formed of a single length of material having the opposite end portions thereof directed inwardly disposed in the same plane with each other and lying parallel to the remaining medial portion with the side edges of said portions folded inward to a superimposed relation and internal concealed means joining said inwardly folded superimposed side edges to provide opposite walls, the end edges of said end portions being free to provide a transverse slit intermediate the ends of one wall of the body whereby to define a pair of pockets extending outwardly from the slit, into which pockets the fingers may be selectively introduced through the slit for manipulating the puff.

11. A powder puff including a body formed of a single length of material having the opposite end portions thereof directed inwardly disposed in the same plane with each other and lying parallel to the medial remaining portion, with the side edges of said portions folded laterally inward to a superimposed relation and internal concealed means joining said inwardly folded superimposed side edges to provide walls of said body, one of which is provided with a transverse slit defined by the unconnected end edges of said end portions; a filler; and a lining within said body, the latter being interposed between the filler and the slotted wall of the body.

12. A powder puff including a body formed of a single length of material having the opposite end portions thereof directed inwardly disposed in the same plane with each other and lying parallel to the medial remaining portion, with the side edges of said portions folded laterally inward to a superimposed relation and means joining said inwardly folded superimposed side

edges to provide walls of said body, one of which is provided with a transverse slit defined by the unconnected end edges of said end portions; a filler; and a lining within said body, the latter being interposed between the filler and the slotted wall of the body, said lining being of greater length than the finished puff body, providing reversely directed ends of said lining for embracing the ends of the filler.
